UNITED STATES PATENT OFFICE

ALTON A. RADLEY, JR., OF WHITEFISH, MONTANA, ASSIGNOR OF ONE-FOURTH TO
JOHN G. HOGAN, OF WHITEFISH, MONTANA

VALVE AND VALVE-SEAT REFINISHING TOOL

Application filed December 16, 1931. Serial No. 581,307.

My present invention relates to improvements in valve and valve-seat refinishing tools of the manually operated type, and adapted especially for use in grinding and truing valves and valve seats for internal combustion engines. The rotary grinding tool of my invention involves the use of a conical head that is designed for interchangeable use as stationary tool holder when grinding the valve, or as a rotary head when grinding the valve seat, and means are provided whereby the necessary changes may be made with facility for these alternate uses.

By the utilization of the device of my invention a grinding tool of this character is provided which is composed of a minimum number of parts which are readily adjustable and changeable for adapting the tool to different uses and to different sizes and shapes of valves and valve seats. The tool is simple both in construction and operation, comparatively inexpensive in cost of manufacture, durable, and efficient in accurately and quickly grinding the valves and their seats.

To this end the invention consists in certain novel combinations and arrangements of parts as will hereinafter be more fully set forth and claimed. In the accompanying drawings I have illustrated one complete example of the physical embodiment of my invention in which the parts are combined and arranged according to the best mode I have thus far devised for the practical application of the principles of my invention.

It will be understood that changes and alterations may be made in the exemplified structure of the drawings, within the scope of my claims without departing from the principles of my invention.

Figure 1 is a vertical sectional view of part of an internal combustion engine showing one of its valves and seat, and the grinding tool also partly in section in position to grind the valve seat.

Figure 2 is a perspective view of the tool head, with its ratchet head removed, and adapted to be clamped in a vise and used as a tool holder for the rotary valve grinding operation.

Figure 3 is a top plan view of the ratchet head (partly broken away for convenience of illustration) which is employed in grinding the valve seat.

Figure 4 is a transverse sectional view at line 4—4 of Figure 1.

Figure 5 is a transverse sectional view at line 5—5 of Figure 3.

Figures 6 and 7 are perspective views of different types of driving heads for use on different types of valves.

In order that the general arrangement, relation of parts, and utility of the invention may readily be understood I have shown in Figure 1 part of the cylinder C and piston P of an internal combustion engine, together with a valve 1 and its stem 2, and the guide bushing 3 for the stem. The valve seat 4 is shown as being ground, and the valve is elevated from its seat in order to accommodate the grinding tool and permit its operation, in grinding and truing the seat, with the tool supported on the stem.

In carrying out my invention, I utilize a hollow cone-shaped tool head 5, which, at the apex of the cone is fashioned with a cylindrical collar 6, and the collar is arranged with diametrically arranged, flat, exterior faces 7, by means of which the head, as a non-rotary holder, may be rigidly clamped between the jaws of a vise when the valve 1 is being ground, it being understood that the valve itself is rotated or revolved within the hollow conical, inverted, head.

At the larger, or upper end of the inverted cone shaped head a cylindrical flange 9 is fashioned, and this flange is formed with four diametrically disposed V-shaped or wedge shaped notches 9'. Within the lower end of the head, and seated in the collar 6, is a removable guide bushing 10, of cylindrical shape, and provided with a flaring flange 11 to support the bushing in the collar at the lower end of the head. Interchangeable bushings are employed, and provided with various sizes of bores to accommodate different sizes of valve stems, and these bushings may be removed and replaced within the collar, with facility and convenience.

In the tapered wall of the tool head are

provided a series of longitudinally extending, vertical slots 12, and these slots are formed with continuations or extensions 13 in the cylindrical or annular flange 9 of the head, as best seen in Figures 1 and 2.

A complementary number of abrading tools, or files 15, are retained in these slots, and the latter are fashioned with tongues 14 in the opposite side walls of the slots 12, for 10 co-action with complementary grooves 16 in the sides of the files. The files are provided with two faces, the outer face for frictional engagement with and grinding of the valve seat, and the inner face for engagement with 15 and grinding of the valve rim or edge.

These files are slipped into the slots of the conical head by first inserting them through the slots 13 of the annular flange, and when the grooves of the files are fitted over the 20 tongues of the slots 12, the files are slid downwardly into the slots, the close frictional contact between the files and the walls of the slots being sufficient to hold the files in place for the grinding operations. As seen in Figure 25 2, the inner faces of the files project within the inner face of the hollow conical tool head, and the outer faces of the files project beyond the outer face of the tool head. The tool heads may be made of different sizes or 30 shapes, that is, the angle of the taper may be acute or obtuse, depending on the angularity of the valve seat and the valve rim or edge, but of course the angularity of the files will be complementary to the angularity of the 35 valve seat and valve-rim, and of course the files on a tool head are all uniformly set for an even grinding or truing of the valve seat or of the valve.

In Figure 1 the tool head is supported on 40 the valve stem and the valve seat, with the valve within the head, and the head is to be rotated so that the abrading tools will grind the valve seat 4.

For revolving the tool head I employ a 45 removable, and reversible ratchet head, which is removed when the valve is to be ground, and which may be reversed or inverted if it is desired to reverse the direction of the rotation of the tool head when grinding 50 a valve seat.

This ratchet head comprises a cup or holder 17 having an angular hole 18 in its bottom, and a cover plate 19 having a circular hole 20 concentric with the hole 18.

55 The holder or cup of the ratchet head is fashioned with an annular set or series of ratchet teeth 21 on its inner face, and a ratchet ring R, having the square hole 18 at its center, is loosely enclosed and retained in the holder. A pair of pawls 22 are diametrically arranged to engage the ratchet teeth and pivoted at 23 on the ring R with springs 24 to retain them in engagement with the ratchet teeth.

60 The ratchet head is of less diameter than

the interior of the open upper end of the tool head, and it is provided with four, diametrically projecting, radial arms 25 having two pairs of beveled faces 26 adapted to fit snugly into the complementary notches 9' of 70 the tool head. When the ratchet head is reversed or inverted these beveled arms are adapted to seat in the notches for use in turning the head 5 in clockwise direction, or in anti-clockwise direction. 75

For turning the tool head, through the instrumentality of the ratchet head a crank 27 is employed, and this crank as shown is square in cross section to fit into and pass through the square hole 18 of the ratchet ring R, while it freely passes through the circular hole 20 in the cover plate of the ratchet head. The ratchet ring turns with the crank and the holder 17 turns with the ring, and through the radial arms 25, the tool head is revolved 80 as the crank is turned.

As a support and guide for the crank, the latter is connected with the valve, as indicated in Figure 1, for grinding the valve seat.

At its lower end the crank is fashioned 90 with a socket 28 and provided with a cotter pin 29 for connection with the valve. In Figures 6 and 7 two types of coupling heads are shown for use with different types of valves, the head in Figure 6 being designed 95 for use with valves having two spaced sockets in their upper faces, and the coupling head in Figure 7 being designed for use with valves having a transverse kerf in their upper faces similar to a screw head. 100

The coupling head in Figure 6 is provided with a pair of spaced pins 30, 30, for engagement in the sockets of the valve, as in Figure 1, and the tapered head 31 with its opening or hole 32 fits into the socket 28 of the crank and is secured therein by means of the cotter pin 29. 105

In Figure 7 the coupling head is fashioned with a blade 33 similar to the end of a screw driver, and the tapered head 31 is secured in the crank socket by means of the cotter pin 32. 110

When the valve is to be ground, it is removed from the engine block, and by means of its flat faces 7, is rigidly clamped in the 115 jaws of a vise, after which the stem of the valve is slipped through the hollow head, and bushing 10. The crank 27 is passed through the ratchet head and coupled with the valve head, and the ratchet head is supported in the stationary, conical, holder 5, by arms 25. The ratchet ring R within the ratchet head, however, revolves with the crank, but in a direction reverse to that which would engage the pawls with the ratchet teeth. 120 The ratchet head thus becomes a stationary support, and the ratchet ring becomes a rotary guide in the ratchet head for the crank as it is turned to grind the valve on the stationary files or abrading tools. Thus, when 125 130

grinding the valve, the crank is turned in direction opposite to that in which it turns when grinding the seat, unless the ratchet head is removed and inverted or reversed as

5 to its position on the crank.

Inasmuch as the conical tool head has a uniformly tapered shape, and the files mounted therein have parallel inner and outer grinding faces, it will be apparent that the
10 taper of the valve seat and of the valve rim is the same, to insure a close and accurate fit of the valve in its seat, after grinding.

From the above description taken in connection with my drawings it will be apparent
15 that the parts of the tool may readily be assembled for use in grinding valve seats, and with equal facility the parts may be dismantled and re-assembled for use in grinding the valves, and the removable and inter-
20 changeable parts may be changed and replaced when necessary with convenience and dispatch.

When it is desired to perform the grinding of the valve and the valve seat at one
25 time and with one operation, this is readily accomplished by the set up of the tool as shown in Figure 1, in which the ratchet will rotate the tool-head to grind or surface the valve seat and the reverse direction of the
30 crank will rotate the valve to grind its rim on edge to a proper fit with the valve seat.

Having thus fully described my invention what I claim as new and desire to secure by Letters Patent is:

35 1. The combination in a tool as described with a hollow, inverted, conical, head having an upper cylindrical flange and notches in said flange, said head having slots therein extending into said flange, and tongues on
40 the opposite side walls of the slots in the head, of complementary files having lateral grooves in sliding engagement with the tongues, a removable rotary driving head, and radially disposed arms on said driving
45 head in engagement in the notches of the flange.

2. The combination in a tool as described, with a hollow inverted conical head having an upper cylindrical notched flange, said head having slots therein extending into said flange, and tongues on the opposite side walls of the slots in the head, of complementary files having lateral grooves in sliding engagement with said tongues, a removable rotary
50 driving head and attaching means thereon for joint use with the notched flange, said conical head having a cylindrical collar at its lower end, a guide bushing seated in the collar, and an upper flaring flange on said bush-
55 ing supported in the conical head.

60 In testimony whereof I affix my signature.
ALTON A. RADLEY, JR.
